1.20 : Top

1.21 : Bottom

(Continued)

The claimed design is a portable television receiver equipped with a light-shielding cover; reproductions 1.1 to 1.7 show a state of the claimed design before change; reproductions 1.8 to 1.14 show an alternate state of the light-shielding cover unfolded halfway upwards; reproductions 1.15 to 1.21 show an alternate state of the light-shielding cover unfolded fully upwards; right views in all dynamic states are omitted because they are mirror images of the left views; the broken lines shown in reproductions 1.1 to 1.21 depict portions of the portable television receiver that form no part of the claimed design; the shading lines are used to show the surface of the claimed design and do not represent its surface ornamentation.
